FIGURE LINK FOR JEWELRY

Samuel D. Goldstein, St. Louis, Mo.

Application June 8, 1942, Serial No. 446,190

1 Claim. (Cl. 63—20)

This invention relates to articles of jewelry, and more particularly to individual units or links of jewelry adapted to be severally purchased and assembled to form a complete bracelet, necklace, anklet, or other form of link jewelry.

An object of the invention is to provide an elongate link upon one face of which is medially represented any desired figure, such as that of an aviator, sailor, marine or soldier, and having a signet or name plate at one end formed with an eyelet or slot in its outer margin, and a stiff yet malleable tongue extended at the opposite end of the figure, whereby a plurality of such links may be releasably connected by successively inserting the tongue of one link through the eye of another link and bending the end of the tongue back against the link.

Another object is to provide as an article of jewelry, an elongate figure link having the figure of a person flatly shown on its outer side in a frontal or face view and extended longitudinally of the link, a name plate joined to the base or foot of the link whereon the name or initials of a person may be written or engraved, a relatively thin grommet extended from the outer end margin of the name plate and at the back of the link, thereby providing at the base an upturned recess or corner lap at the juncture of grommet and name-plate, and a relatively thin, stiff and malleable tongue extended superficially at the head end of the link, thereby providing thereat a down-turned recess or corner lap at the back of the neck of the figure, in reversed relation to the corner lap of the base, whereby a plurality of similar links may be regularly and smoothly joined by successively passing the tongue of one link downwardly through the grommet of another link, drawing the head end of the one link up into the corner recess of the other link, and then bending the tongue sharply up against the back of the link to releasably join the links.

A still further object of the invention is to provide a flat, elongate figure link of the kind referred to, showing in frontal elevation the likeness of a person with head slightly advanced or elevated above or forwardly of the back conformably to nature, a name plate supported upon the feet of the figure, a relatively thin grommet extended longitudinally outwardly of the name plate at the under side thereof, and a relatively thin tongue extended superficially from the opposite end of the figure, whereby, by successively passing the tongues of a plurality of links through the grommets of other links and then

bending them backward, the series of links may be formed into a bracelet or other article of jewelry, with the heads of the several links overlapping the grommets of adjacent links, in a regular, smooth and even formation.

With the stated objects in view, attention is directed to the accompanying drawing, showing one preferred embodiment of the invention, and wherein:

10 Figure 1 is an enlarged plan view of three figure links, as formed in accordance with this invention, and joined together.

Figure 2 is an edge view of the assembly of Figure 1.

15 Figure 3 is a plan view of a single figure link, prior to connecting same in series.

Figure 4 is an edge view of the link of Figure 3.

The invention comprises a figure-link referred to generally at 5, the same being preferably flat and elongate as shown, and made of any suitable metal or other material. The medial portion of the link is conformed substantially to the shape or figure of a person 6, in any character, such as a soldier, sailor, marine or aviator—a frontal elevation of the figure being represented longitudinally along the upper or outer side of the link. The head end of the link is recessed out transversely at the back of the head 7 and neck 8 of the figure, as indicated at 9, this recess

20 may represent or follow the natural forward thrust of the head and neck relative to the body 10 of the figure. A relatively thin tongue 11, of stiff yet bendable material, is extended longitudinally and superficially from the outer or frontal portion of the head end of the link.

25 A name plate 12 is formed and extended at the foot of the figure-link, the superficial showing or configuration preferably though not necessarily being such that the plate 12 would appear 30 to be supported upon the toes 13 and ankles 14 of the figure. (See Fig. 3.) Upon this plate 12 the name or initials of a person may be written or engraved.

35 At the under side or back of the plate 12 a relatively thin grommet 15 is extended longitudinally, said grommet being formed with eye or slot 16, adapted to receive the tongue 11 of an adjacent link, as 5a. Thus there is formed, at the juncture of grommet and name plate of 40 each link, a transverse angular recess or corner 17 adapted to smoothly and evenly receive the head portion 7 of the link 5a, and so on, link after link, until the assembly is of the required length. The joining is completed by inserting the tongues 11 successively down through the

grommets 15 of the added links, and then bending the tongues back and up against the under sides of the links. (See Fig. 2.) In this operation the head portions are drawn up and overlapped onto the grommets, the latter fitting smoothly within the spaces at the back of the head and neck portions of the figure links, thus providing a regular and evenly aligned assembly of links.

There are here shown in Figs. 1 and 2 only three such links as thus joined, but any required number may be connected, to complete a bracelet or the like. The several links are preferably curved, in a conventional manner and as shown, to meet the curvature of the wrist of the wearer.

Any desired changes or alterations in the structures shown may be made, within the scope of the claim.

I claim:

An article of jewelry comprising a series of 20 elongated links each having a back face lying ap-

proximately in a plane and a frontal face impressed to form an ornamental design, a flat elongated tongue of deformable material extending longitudinally from one end of the link and 5 a U-shaped grommet extending longitudinally from the other end of the link, said grommet having one face lying in the plane of the back face but inset from the frontal face of the link and said tongue joining the link at a point offset 10 outwardly from the back face of the link, the distance of offset of the tongue corresponding approximately to the thickness of the grommet, said tongue extending through the grommet of an adjacent link and bent backwardly to form a 15 pivotal connection therewith, whereby the links are coupled together in aligned slightly overlapped relation with the offset at the end of one link forming clearance for receiving the opposite end of an adjacent link.

SAMUEL D. GOLDSTEIN.
